UNITED STATES PATENT OFFICE.

JOHN W. COSGROVE, OF MEDFORD, MASSACHUSETTS, ASSIGNOR TO UNITED SHOE MACHINERY CORPORATION, OF PATERSON, NEW JERSEY, A CORPORATION OF NEW JERSEY.

FASTENING-INSERTING MACHINE.

Application filed March 9, 1922. Serial No. 542,289.

To all whom it may concern:

Be it known that I, JOHN W. COSGROVE, a citizen of the United States, residing at Medford, in the county of Middlesex and State of Massachusetts, have invented certain Improvements in Fastening-Inserting Machines, of which the following description, in connection with the accompanying drawings, is a specification, like reference 10 characters on the drawings indicating like parts in the several figures.

This invention relates to fastening inserting machines and more particularly to machines of this class which have parts relatively movable to clamp the work successively at the points of fastening insertion during the insertion of the fastenings.

As heretofore constructed, machines of the class described commonly comprise a work supporting surface arranged to cooperate with a member, for example, in one type of such machines, the nozzle of a fastening inserting mechanism, in the application at the point of fastening insertion of relatively great pressure which constantly increases up to the termination of the fastening inserting operation, the purpose being to compress the work and insure perfect setting of the fastening. In many of these machines the work support or clinching anvil is so operated as to clamp the work at the point of fastening insertion in a manner comparable to a hammer blow delivered just prior to the ejection of the fastening from the nozzle of the fastening inserting mechanism. For many kinds of work these machines are efficient and satisfactory to a high degree. It will be apparent, however, that with unusually compressible or fragile material such machines as those described would be likely to cause undesirable compression marks or even serious damage to the material at the point of fastening insertion. For instance, in the operation of attaching fur to the edges of the uppers of felt or leather footwear, machines of the type just described would be likely to cut through or otherwise seriously damage the relatively tender skin of the fur.

It is an object of this invention to provide improved means for setting fastenings in materials which are likely to be damaged if the operation be not carried out with relatively light pressure at the point of fastening insertion.

In one aspect the invention resides in an improved means for supporting and clamping the work at the point of fastening insertion so constructed and arranged as to clamp the work with yielding pressure and to be locked in clamping position prior to the insertion of each fastening to insure firm clamping without any harmful effect upon the work, and at the same time perfect setting of the fastening.

The invention contemplates also a locking means for maintaining a work support against retractive movement during the insertion of a fastening in an organization wherein the work support is movable from a work receiving to a work clamping position through the operation of spring means.

In another aspect the invention resides in a single manually operable member for controlling the means for starting the machine and also the means for clamping the work, the organization being such that the work clamping means is locked in its clamping position prior to effective operation of the inserting mechanism so as to hold the work clamping means rigidly against retraction during the insertion of a fastening.

Other features of construction and novel combinations of parts will be described in the detailed specification and pointed out in the appended claims.

In the drawings:—

Fig. 1 is a view in side elevation of one embodiment of the invention.

Fig. 2 is a detail view showing the work clamped between the anvil and nozzle of the stapling mechanism;

Fig. 3 is an enlarged view in side elevation of the anvil operating means;

Fig. 4 is a front view of the machine with parts broken away to show the anvil operating means; and

Fig. 5 is a detail view of portions of the anvil operating means shown in Fig. 3.

Mounted in the overhanging portion 6 of the frame 8 is a stapling head 10 which is preferably, although not necessarily, of the type shown in Patent No. 1,011,592, granted Dec. 12, 1911, on the application of W. J. Drey. In any case the stapling mechanism will comprise a nozzle 12 through which fastenings are driven after having been formed from relatively thin wire drawn from a reel such as that shown at 14 carried at the end of the bracket arm 16. For details of the

fastening forming and driving devices, reference should be had to the patent referred to above.

Power for driving the parts of the stapling mechanism is furnished by the shaft 20 which carries a power pulley 22 arranged to be clutched to the shaft at the will of the operator by any suitable clutch mechanism which may be of the Horton clutch type. A 5 clutch controlling arm 24 is mounted upon a rock shaft 26 and operates normally to hold the clutch in its inoperative condition, the roller cage 28 of the clutch being provided with a stop portion or shoulder 30 which normally engages a spring cushioned dog 32 pivoted between the ears 34 upon the end of the arm 24. When the shaft 26 is turned in a counter clockwise direction in Fig. 1, the dog 32 is lifted out of engagement with the stop or shoulder 30 and the roller cage 28 is rotated by a spring (not shown) in the usual manner to bring the rollers of the Horton clutch into clutching position between a clutch member fixed on 10 the shaft 20 and a cylindrical surface upon the inside of the pulley 22. A spring 36 tends to maintain the arm 24 normally in its clutch releasing position. For rotating the clutch controlling arm 24 in a direction away 15 from the clutch there is provided manually controlled means which, in the illustrative construction, comprises a treadle 40 pivoted at 42 upon a support 44 secured to the floor or to a portion of the machine frame, the 20 treadle having a tread portion 41. Connected to the far end of the treadle lever 40 is a rod 46 which may be extensible in any well known manner, as for instance by a double 25 collar 48 through which pass the upper and lower parts of the rod 46, means being provided such as set screws for securing the collar and the rod parts in adjusted relation to each other. At its upper end the rod 46 is pivoted at 52 to one end of a lever arm 30 30 which is keyed on its other end to a shaft 56 supported in bearings in the frame of the machine. Extending upwardly from the shaft 56 is a second lever arm 58 which is conveniently bifurcated as most clearly 35 shown in Fig. 4 to straddle one end of a link 60, the bifurcated portion of the arm 58 being provided with a pin or bolt 62 which is adapted to engage with the hooked end 64 of the link 60. As illustrated the link 60 is maintained in engagement with the pin 62 by means of a spring 66. At the end opposite to its hooked end the link 60 is pivoted at 68 to an arm 70 carried by or secured to the shaft 26. When the treadle lever 40 40 has its tread portion 41 depressed the upper end of the lever arm 58 is moved to the right in Figs. 1 and 3, the pin 62 sliding along the upper edge surface of the link 60 until it engages with the hooked end 64 of the link, 45 thus providing a lost motion connection be-

tween these parts which has a purpose that will be pointed out later in this specification. Upon engagement of the pin 62 with the hook 64 during continued movement of the arm 58 the link 60 is carried to the right, 70 thus rocking the shaft 26 and withdrawing the lever arm 24 from contact with the stop 30 on the cage 28 of the clutch, whereupon the clutch is permitted to operate to connect the power pulley 22 with the shaft of the 75 machine.

For supporting the work at the point of fastening insertion there is provided a member 80 which is preferably also an anvil member having a clinching cavity at its end in alignment with the line of fastenings driven through the nozzle 12. As shown, the anvil 80 is a separate member secured in the end of a support 82 which is conveniently of the shape shown in order that shoes or slippers or similarly shaped articles may be readily positioned with the forward end of the anvil entering the article to be operated on. In the illustrative construction the support 82 has a straight portion or post 84 which is 80 slidable vertically in a bearing 86 fixedly secured to the frame portion of the stapling head 10, there being a removable cover portion 88 whereby the assembly of the parts may be made in an easy and expeditious manner. Preferably the upper part of the straight portion 84 of the support 82 is reduced in diameter and is surrounded by a spring 94 (Fig. 5), washers 96 and 98 being provided at each end of the spring 94 slidable on the post 84. Fixed to the shaft 56 already described is an arm 100 (Fig. 5) which has a bifurcated end 102 arranged to embrace the upper end of the post 84 and which has rounded end portions 104 upon which rests the lower washer 98, the latter being constantly kept in contact with the end of the lever 100 through pressure of the spring 94. When the lever arm 100 is rocked in a 105 clockwise direction the washer 98 is moved upwardly, compressing the spring 94 and, through this yielding connection, lifting the support 82 of the combined anvil and work support 80. It will be recalled that the shaft 56 is rocked through direct connections with the treadle lever 40 and that there is a lost motion connection between the treadle and the clutch controlling lever 24. Hence, when the tread portion 41 of the treadle lever 40 is depressed, the first result is to move the anvil in an upward direction yieldingly through the spring 94 to press the work against the end of the nozzle 12, the tension of the spring 94 being preferably such that the clamping pressure upon the work may be relatively light for certain classes of work, as for instance in stapling fur around the top edge portions of felt slippers, as indicated in Fig. 2 of the drawings, this being 110 one of the purposes for which the machine 115

is especially adapted. While the spring 94 may be depended upon to supply sufficient clamping pressure upon the work, there is preferably provided a second spring 110 secured to the upper end of the post 84 above the spring 94 and at its other end to a hook 112 upon a stationary part of the frame. This spring 110 serves also as a means tending to maintain the post 84 in a vertical position so that it will slide readily through its bearing 86. Without the spring 110 there is a tendency of the upper end of the bar 84 to move toward the right in Fig. 5 because of friction between the ends 104 of the 15 lifting lever 100 and the contracted surfaces on the washer 98.

While it is eminently desirable that the work in certain cases should be clamped against the nozzle of the fastening inserting mechanism with such a pressure that no damage to the work will ensue, it is both necessary and desirable that the support should furnish sufficient resistance to the action of the fastening driving parts to ensure that the fastening will be securely set in the work. Accordingly, means is provided for locking the anvil in the position to which it has been moved by the operation of the spring means, the said locking means comprising, in the illustrative construction, a pivoted member 116 having a passageway which fits closely upon the straight portion or post 84 of the anvil support 82. Conveniently, the bearing 86 is provided with a 30 couple of slots 118 for slidably receiving the flat ends 120 of a cylindrical bearing pin 121 which is rotatable within an enlarged bearing portion of the locking member 116, the arrangement being such that the member 35 116 pivots on the pin 121 and is capable of a slight lateral movement due to the slidable mounting of the flat ends 120 of the pin 121 in the slots 118 of the box or bearing 86. In the free end of the member 116 there is 40 mounted a bearing pin 122 secured adjustably in place by a lock nut 124, the arrangement being such that the lever arm 100 when in its lowermost position of rest normally contacts with the bearing pin 122 to 45 hold the main or ring portion 130 of the member 116 in a plane perpendicular to the long axis of the post 84 so that the bar may slide readily through the passage in the ring 130. As soon, however, as the lever member 50 100 starts upwardly upon depressing the treadle lever 40, the member 116 is freed from the control of the said lever member 100 so that the ring 130 may move to another position other than the horizontal, means being provided for ensuring 55 that the ring will take this other position, such means being shown as a spring pressed plunger 140 mounted for sliding movement in the bearing 86 under the action of the spring 142, the tension of which

may be adjusted through proper manipulation of a screw threaded member 144. The tension of the spring 142 is such that upward sliding movement of the bar 84 may readily take place even after the lever 100 70 is separated from the bearing pin 122, because friction between the ring 130 and the post 84 tends to carry the ring back into the horizontal plane so that the bar can slide readily through the opening in the ring. 75 Any movement of the post 84 in a downward direction because of friction of the parts just referred to will aid the spring 142 in moving the ring 130 to clamping position with respect to the post 84 so that the ring acts as 80 an absolute lock to hold the post 84 against downward movement. The post 84 and, therefore, the anvil 80, will remain locked against downward movement until the lever arm 100 returns to its initial position upon 85 release of the treadle. When this takes place the contact of the lever 100 with the bearing pin 122 immediately returns the lock ring 130 to the horizontal plane, in which position it no longer has a locking action on the 90 post. Thus, the anvil with its support immediately drops to the work receiving position illustrated in Fig. 1 of the drawings. Since the locking means for the work support 80 is constructed to be separate from 95 the work support lifting means, the locking means cannot be utilized to place additional clamping pressure on the work as in the prior constructions with which applicant is acquainted.

For insuring that the ring 130 will act efficiently as a clutch or lock to grip the bar 84, its inner ring portion has beveled off portions, the bevels being in different planes and pointing in opposite directions, as indicated 100 in Fig. 5 of the drawings. By reason of the bevels, the surface contact with the post 84 is reduced and a slight turning movement of the ring 130 relatively to the post 84 is 105 permitted by which the latter is firmly gripped.

In operating with the machine the work is introduced over the anvil member 80 and positioned properly for the insertion of a 115 staple. Upon depressing the treadle lever 40, the lever arm 100 is moved upwardly to elevate the anvil yieldingly through the spring 94, clamping the work more or less lightly in accordance with the tension of the 120 spring 94. Any downward movement of the anvil is prevented by the clutch or lock ring 130 which is constantly in operation to prevent such movement as soon as the lever arm 100 starts upwardly. All of this takes place prior to the throwing in of the clutch, the latter being effected by the lost motion connection furnished by the pin 62 and the hook end 64 of the link 60 by which movement of the treadle lever is transmitted to 125 the clutch controlling lever 24. With the 130

work supported on the anvil and the latter locked against downward movement, the fastening is driven and securely set into the work. Upon release of the treadle the parts 5 return to their normal position and the work may be removed or shifted preliminary to the insertion of another fastening.

Having described my invention, what I claim as new and desire to secure by Letters 10 Patent of the United States is:—

1. In a machine of the class described, fastening inserting mechanism, a work support, means operative through the work support yieldingly to press the work in 15 clamping relation to the inserting mechanism, and means for locking the work support against retractive movement only, the locking means serving to hold the work support rigidly against retraction while a 20 fastening is being inserted into the work.

2. In a machine of the class described, fastening inserting mechanism comprising a nozzle through which fastenings are driven, a support for work, means operative 25 through the work support for yieldingly pressing work on the support against the end of the nozzle, and locking means for preventing retraction of the work support while permitting movement thereof in work 30 clamping direction.

3. In a machine of the class described, fastening inserting mechanism comprising a stationary nozzle through which fastenings are driven, a member for yieldingly 35 pressing the work against the nozzle, and means for locking the member against retraction only, the locking means being operative to hold the member rigidly against retraction during insertion of a fastening.

40 4. In a machine of the class described, fastening inserting mechanism comprising a nozzle through which fastenings are driven, an anvil for co-operating with the inserting mechanism for setting the fastenings in the work, a manually operable member for controlling both the inserting mechanism and the anvil, spring means for moving the anvil yieldingly toward the nozzle to clamp the work with a relatively light pressure, 45 and means for locking the anvil in its clamping position prior to the insertion of a fastening, the construction being such that the anvil is rigidly supported during the insertion of a fastening.

55 5. In a machine of the character described, fastening inserting mechanism comprising a nozzle through which fastenings are driven, an anvil movable toward and from the nozzle, means for moving the anvil to press the work yieldingly against the nozzle, means for starting the fastening inserting mechanism in operation, and means controlled directly by the starting means 60 for locking the anvil against retraction and in the position to which it has been moved

by the first-mentioned means, the locking means being independent of the moving means for the anvil so that the locking means is operative only to maintain pressure applied by the moving means. 70

6. In a machine of the character described, fastening inserting mechanism comprising a nozzle through which fastenings may be driven into work properly presented thereto, an anvil movable toward and from the nozzle, means for causing the anvil to press the work yieldingly against the nozzle, starting means, means for locking the anvil against movement away from the extreme clamping position to which it has been moved by the first-mentioned means, and a lost motion connection between the starting means and the anvil locking means whereby the anvil is locked prior to the insertion of a fastening by said mechanism, the anvil and the locking means being relatively movable at all times in one direction so that the locking means cannot be used to place the work under greater pressure than that caused by the first-mentioned means. 75 80 85

7. In a machine of the character described, fastening inserting mechanism comprising a nozzle through which fastenings are driven, an anvil for pressing the work yieldingly against the nozzle, a supporting member for the anvil, starting means for the machine comprising a treadle, spring means operated by force applied from the treadle for lifting the anvil support to cause the latter to press the work yieldingly against the nozzle, and a lock for the anvil support arranged to be released by the starting means in such manner as to become operative as a locking means before the insertion of a fastening 90 95 100

105 8. In a machine of the character described, fastening inserting mechanism comprising a nozzle through which fastenings are driven, a member for pressing the work yieldingly against the nozzle and operating means therefor, starting means for the inserting mechanism, a lock for engaging with the pressing member to lock the same against retraction, and a single manually operable member for controlling the starting means and the lock, the latter and the operating means for the work pressing member being independent of each other so that no additional pressure can be placed 110 115 120 upon the work with the co-operation of the lock.

9. In a machine of the character described, fastening inserting mechanism comprising a nozzle through which fastenings are driven, an anvil for clinching fastenings, starting means comprising a clutch and clutch controlling lever for starting the machine in operation, a treadle, a lost-motion connection between the treadle and the clutch controlling lever for moving the lat- 125 130

- ter to initiate operation of the machine, a spring for supporting the anvil, connections between the treadle and the spring for compressing the latter whereby the anvil is moved to clamp the work yieldingly against the nozzle without damage to the work, and a lock for the anvil controlled by the starting means and operative to prevent retraction of the anvil through compression of the spring during the insertion of a fastening. 5
10. In a machine of the character described, fastening inserting mechanism comprising a nozzle through which fastenings are driven, starting means comprising a clutch lever for controlling the operations of the said mechanism, an anvil for clinching the fastenings, means for moving the anvil to clamp the work against the nozzle 15 and a lock for engagement with the anvil and operative prior to the insertion of each fastening, for locking the anvil against retraction and a lost motion connection between the lock and the clutch lever whereby the lock becomes operative prior to the insertion of a fastening. 20
11. In a machine of the character described, fastening inserting mechanism comprising a nozzle through which fastenings are driven, an anvil movable toward and from the nozzle, a spring for engagement with the anvil for moving the anvil to clamp the work yieldingly against the nozzle, a lock for engagement with the anvil to lock 25 the latter against movement to compress the spring, the construction being such that the anvil may be moved at all times toward clamping position, and means for returning the lock to inoperative position. 30
40. 12. In a machine of the class described, a fastening inserting mechanism comprising a nozzle through which fastenings are driven, an anvil movable toward and from the nozzle, a supporting member for the anvil, a spring for moving the anvil yieldingly to clamp the work against the nozzle, a pivoted lock member having an opening through which the anvil support passes, a spring for moving the lock to operative position, starting means for the machine, and connections between the starting means and the lock for moving the latter to inoperative position. 45
50. 13. In a machine of the character described, a fastening inserting mechanism comprising a nozzle through which fastenings are driven, an anvil movable toward and from the nozzle, a spring for causing the anvil yieldingly to clamp work against the nozzle, a support for the anvil, a lock having an opening therein through which the anvil support passes, a spring for moving the lock to operative position, the construction and arrangement being such that the anvil support may move in work clamp- 55
- ing direction with the lock in operative position, starting means for the machine, and connections from the starting means to the lock for moving the latter to inoperative position following the insertion of the fastening. 70
14. In a machine of the character described, fastening inserting means comprising a nozzle through which fastenings are driven, an anvil movable toward and from the nozzle, a support for the anvil, a bearing for slidably receiving the anvil support, a spring for moving the anvil support in a direction to cause clamping of the work by the anvil, a lock pivoted in the bearing and having an opening through which the anvil support slides, and a spring for moving the lock toward operative position, the construction and arrangement being such that the spring will yield to permit movement of the anvil support in a direction to cause clamping of the work while at the same time being effective to hold the lock in such position as to prevent retraction of the anvil during a fastening 80 inserting operation. 85
15. In a machine of the class described, a fastening inserting mechanism comprising a nozzle through which fastenings are driven, a work support movable toward and from the nozzle and comprising a post, means for moving the support to clamp the work against the nozzle, a pivoted lock member having an opening through which the post passes, means for moving the lock about its pivot point to cause it to grip the post, starting means for the machine, and connections between the starting means and the lock for moving the latter to inoperative position. 90
16. In a machine of the character described, a fastening inserting mechanism comprising a nozzle through which fastenings are driven, a work support movable toward and from the nozzle and comprising a post, means for causing the support to clamp the work against the nozzle, a lock having an opening therein through which the post passes, a spring for moving the lock to operative position, the construction and arrangement being such that the support may move at all times with relation to the lock in the work clamping direction, starting means for the machine, and connections from the starting means to the lock for moving the latter to inoperative position following the insertion of the fastening. 100
17. In a machine of the character described, fastening inserting means comprising a nozzle through which fastenings are driven, a work support movable toward and from the nozzle, and comprising a post, a bearing for slidably receiving the post, a lock pivoted in the bearing and having an opening through which the post slides, and 110
18. In a machine of the character described, fastening inserting means comprising a nozzle through which fastenings are driven, a work support movable toward and from the nozzle, and comprising a post, a bearing for slidably receiving the post, a lock pivoted in the bearing and having an opening through which the post slides, and 115
19. In a machine of the character described, fastening inserting means comprising a nozzle through which fastenings are driven, a work support movable toward and from the nozzle, and comprising a post, a bearing for slidably receiving the post, a lock pivoted in the bearing and having an opening through which the post slides, and 120
20. In a machine of the character described, fastening inserting means comprising a nozzle through which fastenings are driven, a work support movable toward and from the nozzle, and comprising a post, a bearing for slidably receiving the post, a lock pivoted in the bearing and having an opening through which the post slides, and 125
21. In a machine of the character described, fastening inserting means comprising a nozzle through which fastenings are driven, a work support movable toward and from the nozzle, and comprising a post, a bearing for slidably receiving the post, a lock pivoted in the bearing and having an opening through which the post slides, and 130

- a spring for moving the lock toward operative position, the construction and arrangement being such that the spring will yield to permit movement of the work support in a direction to cause clamping of the work while at the same time being effective to hold the lock in such position as to prevent retraction of the support during a fastening inserting operation.
18. In a machine of the character described, an abutment and a work support normally spaced relatively to each other in work receiving and work feeding position and relatively movable to engage work on the support with a clamping pressure, spring

means for causing such relative approaching movement, means for locking one of the work engaging members (the support and the abutment) against retraction relatively to the other member, the locking means being independent of the means for causing approaching movement of the members, and means for rendering the locking means inoperative thereby initiating return of the work engaging members to work receiving position.

In testimony whereof I have signed my name to this specification.

JOHN W. COSGROVE.
